WALTER L. CHURCH, OF HOUSTON, TEXAS, ASSIGNOR OF ONE-HALF TO WILLIAM L. PEARCE, OF HOUSTON, TEXAS

CASING CUTTER

Application filed August 2, 1926. Serial No. 126,426.

This invention relates to new and useful improvements in a casing cutter.

One object of the invention is to provide an implement of the character described specially designed for use in cutting casing, or pipe, stuck in a well bore, so that the same may be withdrawn a section at a time.

Another object of the invention is to provide an implement of the character described, embodying a cutter body with radially movable cutters and means operable by fluid pressure to force the cutters into engagement with the pipe to be cut, as the cutter is rotated.

A further object of the invention resides in the provision of means through which the fluid may be cut off and the cutters released, for withdrawal, as soon as the casing or pipe has been severed.

A still further feature of the invention resides in the provision of a novel type of cutter employed.

With the above and other objects in view this invention has particular relation to certain novel features of construction, operation, and arrangement of parts, an example of which is given in this specification and illustrated in the accompanying drawings, wherein:

Figure 1 shows a vertical sectional view of the implement showing the cutters partially projected, and

Figure 2 shows a plan view of the cutters in operative relation with the mandrel associated therewith, and showing the body in section on the line 2-2 of Figure 1.

Referring now more particularly to the drawings, wherein like numerals of reference designate similar parts in each of the figures the numeral 1 designates a cutter body having the axially movable mandrel 2, therein, whose lower end is tapered and works between the oppositely disposed cutters 3, 3, which are radially movable in radial slots or bearings in the body 1. Attached to the lower end of the body there is a conventional drill bit 4,

provided to remove from the casing, or pipe, to be cut, any deposits that may have settled therein so as to permit the cutter to be lowered in the pipe to be cut. There are flat springs 5, 5, attached at their upper ends to the body, on opposite sides and the lower ends of these springs rest against the shoulder 6, 6, carried by the upper sides of the cutters 3 and retain the cutters in their bearings. The upper end of the body is formed with a cylinder 7 and within the cylinder there is a suitable plunger 8, carried by the mandrel 2. A coil spring 9 rests on the bottom of said cylinder and surrounds the mandrel 2 and the plunger 8 rests against the upper end of this spring.

Secured to the upper end of the cylinder 7 there is a spider 10 having a fluid passageway into the cylinder and which supports the valve seat 11 and cooperating with said seat there is an upwardly opening ball valve 12 which is confined by the conventional valve cage 13 screwed onto said seat. The valve 12 is disposed above and is aligned with and normally supported by the upper end of the mandrel 2 which extends up through said passageway. The valve 12 is arranged above said seat, and controls said passageway.

In operation the implement will be attached to the lower end of the string of pipe and will be thereby lowered into the casing to be cut. If the casing is filled with earth formation the implement may be rotated and the bit 4 will disintegrate such formation so that it may be washed out until the cutter is lowered to the desired point.

Water, under pressure, is then pumped down through the string of pipe to which the cutter is attached and will pass down through the seat 11 and will force the plunger 8 downwardly compressing the spring 9 and as the plunger moves downwardly the mandrel 2 will be forced downwardly through the axial bearing 14 of the head 1 and its tapered lower end will work against the downward

converging faces 15, 15, of the cutters 3 and force said cutters outwardly into contact with the casing to be cut. Meanwhile the cutter is rotated and as cutters 3, 3, are forced outwardly they will gradually penetrate and eventually sever the casing to be cut.

5 The plunger 8 has restricted water courses 16, 16, therethrough through which a part of the pressure fluid is permitted to pass, said fluid passing through the bearing 14 and out 10 through the water course 17 provided in the bit. These channels 16, 16, are provided so that the pump may continue to operate and will not be completely stopped.

15 When the tapered lower end of the mandrel passes through between the cutters 3, and said cutters are fully expanded or projected the casing to be cut will be severed and the valve 12 will seat on the seat 11 and block the flow of fluid downwardly. When 20 this happens the pump will be stopped, indicating to the operator that the casing has been entirely severed and thereupon the spring 9 will lift the plunger 8 carrying the mandrel 2 upwardly with it and releasing 25 said mandrel from the cutters 3 and lifting its valve 12 from its seat.

It is to be noted that the outer edge or 30 margin of each cutter is serrated as at 18 so as to more readily cut into the casing and furthermore that the teeth of said cutters are 35 tapered or formed wedge-shaped. When the casing has been severed an upward pull may be exerted on the implement through the 40 stem 1 and the sloping upper side of the teeth contacting against the lower end of the severed section, and assisted by the springs 5, 5, will force the cutters inwardly so that the implement may be withdrawn.

45 What I claim is:

1. A device of the character described including a body, a fluid pressure cylinder associated therewith, a plunger in said cylinder, a valve controlling the admission of pressure fluid into said cylinder, radially movable cutters in said body, a mandrel connected to the plunger and whose lower end is adapted to work between said cutters and whose upper end is aligned beneath said valve, a yieldable member associated with the mandrel and normally holding the same in position to release said cutters and to hold said valve open, means connected to said cutters and normally tending to move them inwardly relative to said body.

55 2. A device of the character described including a body radially movable cutters therein, a cylinder associated with said body, a plunger therein; an axially movable mandrel in the body connected to the plunger and having a tapering portion adapted to work between the cutters to project the same outwardly, an upwardly opening valve adapted to control the inlet of pressure fluid into said cylinder above the plunger, a yieldable mem-

ber normally holding the said mandrel in inoperative relation with said cutters with its upper end in position to support said valve in open position.

3. A device of the character described including a body, radially movable cutters therein, a cylinder associated with said body, a plunger therein, an axially movable mandrel in the body connected to the plunger and having a tapering portion adapted to work between the cutters to project the same outwardly, an upwardly opening valve adapted to control the inlet of pressure fluid into said cylinder above the plunger, a yieldable member normally holding said mandrel in inoperative relation with said cutters with its upper end in position to support said valve in open position and means normally tending to move said cutters inwardly.

4. A device of the character described including a cutter body, radially movable cutters associated therewith, a cylinder associated with said body, a plunger in said cylinder, a mandrel axially movable in said body and to which the plunger is fixed, said cylinder having an inlet passageway, a valve controlling said passageway and normally held in open position by said mandrel, to admit fluid under pressure into said cylinder whereby said plunger and mandrel may be actuated in one direction to project said cutters outwardly and permit the closing of said passageway by said valve.

5. A device of the character described including a cutter body, radially movable cutters associated therewith, a cylinder associated with said body, a plunger in said cylinder, a mandrel axially movable in said body and to which the plunger is fixed, said cylinder having an inlet passageway, a valve controlling said passageway and normally held in open position by said mandrel, to admit fluid under pressure into said cylinder whereby said plunger and mandrel may be actuated in one direction to project said cutters outwardly and permit the closing of said passageway by said valve and means normally tending to actuate the plunger and mandrel in the other direction.

6. A casing cutter including a body, a fluid pressure cylinder associated therewith, a plunger in said cylinder having a restricted water course therethrough, said cylinder having an inlet passageway, a valve controlling said passageway, radially movable cutters in said body, a mandrel connected to the plunger whose lower end is adapted to work between said cutters and whose upper end is extended up through said inlet passageway and aligned underneath the valve, a yieldable member associated with the mandrel and normally holding the same in position to release said cutters and to hold said valve open.

7. A device of the character described including a body, a fluid pressure cylinder as-

sociated therewith, a plunger in said cylinder, a valve controlling the admission of pressure fluid into said cylinder, radially movable cutters in said body, a mandrel connected to the plunger whose lower end is adapted to work between said cutters and whose upper end is aligned beneath said valve, a yieldable member associated with the mandrel and normally holding the same in position to release said cutters and to hold said valve open.

10 In testimony whereof I have signed my name to this specification.
